UNITED STATES PATENT OFFICE.

ARTHUR SOSS, OF SEWARD, NEBRASKA.

VALVE-OPERATING MECHANISM.

1,218,010.

Specification of Letters Patent.

Patented Mar. 6, 1917.

Application filed July 5, 1916. Serial No. 107,699.

To all whom it may concern:

Be it known that I, ARTHUR Soss, a citizen of the United States, residing at Seward, in the county of Seward and State of Nebraska, have invented new and useful Improvements in Valve-Operating Mechanism, of which the following is a specification.

This invention relates to valve operating mechanisms for gas engines and has as one of its objects to provide an actuating mechanism so constructed as to insure of proper seating of the valve during the working stroke of the piston. In the ordinary mechanisms of this class, the push rod which coacts with the valve stem is liable to expand to such an extent, through the heat from the engine, as to prevent the valve seating snugly upon its seat, or if it is adjusted so as to insure of proper seating of the valve regardless of expansion of the parts, noise will likely be created through knocking of the actuating cam against the push rod or through knocking of the push rod against the lower end of the valve stem.

The present invention therefore aims to provide a push rod so constructed that the upper end thereof will at all times engage against the lower end of the valve stem and the lower end against the actuating cam, and yet provide for expansion and contraction of the push rod and valve stem. In this manner proper seating of the valve is insured and at the same time, the operation of the valve is noiseless as there is no actual separation of the parts as the valve becomes seated.

In the accompanying drawings:

Figure 1 is a vertical sectional view through the device embodying the present invention applied, the valve being shown open, and

Fig. 2 is a similar view, the valve being shown closed.

In the drawings, the numeral 5 indicates in general the cylinder of a gas engine and 6 a valve casing associated therewith. The valve casing is provided with a seat 7 for the valve which is indicated by the numeral 8, and which has a stem 9 working in a suitable bushing 10 fitted through the lower end of the valve casing. A spring 11 bears at its upper end against the lower end of the valve casing and at its lower end against a suitable stop 12 upon the said stem, and this spring tends to lower the valve to its

seat. The oil-containing crank case of the engine is indicated by the numeral 13 and working in the same is a cam shaft 14 carrying the actuating cam 15 for the valve, 60 the said cam being designed to coact with the push rod, which latter in turn, coacts with the lower end of the valve stem as will now be explained.

The push rod of the present invention includes a section 16 which is exteriorly cylindrical and which is formed in its lower portion with a smooth bore 17 and in its upper portion with a threaded bore 18 adjustably receiving an abutment screw 19 70 which is held at adjustment by means of a jam nut 20 threaded thereon and bearing against the upper end of the section 16. As clearly shown in the drawings, the lower end of the valve stem 9, rests upon the head 75 of the abutment screw 19 in both the open and closed positions of the valve. The section 16 of the push rod is slidably mounted in a suitable bearing 21 on the top of the crank case 13 and extends at its lower end 80 into the crank case, where it is provided with a head 22 having a flat under side, the head being concentric to the bore 17 of the said section. The lower section of the push rod includes a stem 23 which carries at its 85 lower end an oil pocket 24. A cushioning disk 25 of fiber or leather, or any other suitable material, rests in the bottom of the oil pocket 24 beneath the head 22. The stem 23 is slidably fitted within the bore 17 90 in the lower portion of the upper section of the push rod and the head 22 is received within the pocket 24. A spring 26 is fitted within the upper end of the bore 17 and bears at its upper end against the inner end 95 of the bore and at its lower end against the upper end of the stem 23. The tendency of the spring is of course to separate the sections of the push rod and it therefore yieldably holds the head end of the abutment screw 19 against the lower end of the valve stem 9, and also holds the under side of the oil pocket 24 against the working face of the actuating cam 15.

The oil pocket is kept filled or substantially filled with oil contained within the crank case and by reference to Fig. 2 it will be observed that when the valve is resting upon its seat and the under side of the oil pocket is resting upon the inactive portion of the cam there will be a slight space 110 between the under side of the head 22 and

the upper face of the cushioning disk 25 into which oil may enter for the purpose of cushioning the contact of the said head and disk as the active portion of the cam rides beneath the oil pocket in lifting the valve from its seat. It will be apparent that while there is play between the sections of the push rod, the movement of the parts is cushioned in a manner to obviate noise and shock. It will also be apparent that the valve stem and the push rod may expand and contract without affecting the operation of the device and without in any way interfering with the proper seating of the valve during the working stroke of the piston.

I claim:

1. In a device of the class described, relatively slideable sections, means tending to separate the sections, a pocket carried by one of the sections for containing a cushioning fluid, and an impact receiving member of yieldable material arranged within the said pocket.

2. In a device of the class described, the combination with a valve and its stem, and an actuating member for the valve, of a push rod connection between the said stem and the said actuating member including relatively slidably connected sections, means tending to separate the sections, an adjustable abutment carried by one of the sections and engaging the said valve stem, an oil pocket carried by the other section, the under side of the said oil pocket engaging the said actuating member, the first mentioned member being provided with a head working in the oil pocket, and a cushioning disk arranged within the oil pocket and constituting an abutment for the said head.

In testimony whereof I affix my signature.
ARTHUR SOSS.
